Alphonse Roos

UNITED STATES PATENT OFFICE.

ALPHONSE ROOS, OF CHICAGO, ILLINOIS.

ADJUSTABLE SERVING STAND.

Application filed April 20, 1922. Serial No. 555,672.

To all whom it may concern:

Be it known that I, ALPHONSE Roos, a citizen of France, residing at Chicago, in the county of Cook and State of Illinois, have 5 invented certain new and useful Improvements in Adjustable Serving Stands, of which the following is a specification.

This invention relates to improvements in serving stands and has for its object to provide an adjustable serving stand.

Another object of the invention is to provide an adjustable roller bearing serving stand.

A still further object of the invention is 15 to provide a carriage having an adjustable roller stand mounted thereupon.

With the above and other objects in view I have invented the device illustrated in the accompanying drawings, in which—

20 Figure 1 is an elevational view of a serving stand;

Figure 2 is a top plan view thereof;

Figure 3 is a section on line 3—3 of Figure 2; and

25 Figure 4 is a section on line 4—4 of Figure 1.

Like reference characters indicate like parts throughout the following specification and in the several views in the drawings in 30 which, 1 indicates a serving stand which consists of a carriage 2, mounted upon universal wheels or castors 3, whereby the stand when used as a serving stand may readily be moved from one part of the table to another 35 or whereby when it is used as a small display stand it may be readily moved about on the counter or, when used as a large display stand it may be readily rolled along on the floor, a carriage 2 preferably cone shaped, 40 from the apex 4 of which projects a vertical rod 5 having a series of apertures 6 therein extending throughout its entire length.

Mounted upon the rod 5 is a cross arm support 7 for the revolvable tray 8 said member 45 7 being fixed to the collar 9 having an aperture adapted to align with any of the apertures 6 through which a pin 10 may be projected to hold said collar in any desired position upon the rod 5. The arms 11, 12,

50 13 and 14 of the member 7 are provided on their outer ends with rollers 15 upon which the tray 8 is seated said tray having a central aperture (not shown) through which the rod 5 projects.

55 Mounted on the rod 5 above the tray 8 is an adjustable collar 16 provided with rollers

17 which seat down upon the tray 8 in order to steady the same. Mounted upon the rod 5 above the tray 8 is another tray 18 having an enlarged central portion 19 provided with an annular groove 20 in which projects the annular flange 21 of the adjustable collar 22 which is slidably mounted on the rod 5. Roller bearings 23, 24, and 25 hold the members 18 and 20 out of frictional engagement with one another and form a ball bearing between said members. The collar 22 is provided with apertures 26 adapted to align with the openings 6 of the rod 5 to receive the pins 27 whereby the tray 18 is held in a 70 desired adjusted position on said rod 5. Both of the trays 8 and 18 are provided with peripheral rods 28 and 29 respectively, whereby said stands may be conveniently rotated. The stand 18 may be provided 75 with a series of apertures 30 in which reduced ends of condiment holders may seat. A handle 31 may be provided on the upper end of the rod 5 whereby the device may be conveniently carried from place to place. The member 16 is provided with an extension collar 16' having an aperture aligning with the aperture 6 through which a pin 16^a projects to hold the member 16 down against the tray 8.

80 The above described stand may be used either as a server for dining tables or it may be used as a display stand for store counters, or if made on an enlarged scale it may be used as a display stand to be operated upon the floor of a store or other place. As a server the articles on the stands may be very easily gotten at by anyone at the table and as a display stand the stand may be rotated by an observer or prospective customer and a large number of articles displayed on the stand examined with little or no difficulty.

Having described my invention that which I claim to be new and desire to procure by Letters Patent is:—

1. A device of the character described consisting of a carriage having an upright and adjustable trays on said upright, roller bearing supports for said trays, a steadyng member for one of said trays, roller connections between said member and said last tray.

2. A device of the character described consisting of a carriage having universal rollers and an upright thereon, an adjustable revolving tray on said upright and a

handle on said upright, a steadyng device for said tray adjustably carried by said upright, a turn-table for said tray.

3. A device of the character described consisting of a carriage having universal rollers and an upright thereon, an adjustable revolving tray on said upright and a handle on said upright, a steadyng device for said tray adjustably carried by said upright, a turn-table for said tray, an additional adjustable tray on said upright.

4. A device of the character described consisting of a carriage having universal rollers and an upright thereon, an adjustable revolving tray on said upright and a handle on said upright, a steadyng device for said tray adjustably carried by said upright, a turn-table for said tray, an additional adjustable tray on said upright, said latter tray

having a central enlargement with an annular recess therein and a turn-table mounted within said recess. 20

5. A device of the character described consisting of a carriage having an upright and adjustable trays on said upright, roller bearing supports for said trays, a steadyng member for one of said trays, roller connections between said member and said last tray, universal wheels for said carriage, and means for holding said steadyng device in 25 engagement with said first tray. 30

In testimony whereof I affix my signature in the presence of two witnesses.

ALPHONSE ROOS.
